UNITED STATES PATENT OFFICE.

CLAUD E. MILLS, OF DES MOINES, IOWA.

COMBINED INTAKE AND EXHAUST MANIFOLD.

1,317,379.

Specification of Letters Patent. Patented Sept. 30, 1919.

Application filed May 29, 1918. Serial No. 227,281.

To all whom it may concern:

Be it known that I, CLAUD E. MILLS, a citizen of the United States, and resident of Des Moines, in the county of Polk and State of Iowa, have invented a certain new and useful Combined Intake and Exhaust Manifold, of which the following is a specification.

The object of my invention is to provide a fuel preparing device of simple, durable and inexpensive construction, adapted to be used in connection with internal combustion engines, and adaptable for all carbureters.

More particularly it is my object to provide such a device which may be made as a unitary structure and assembled on an engine as an attachment therefor, and which will serve to break up and thoroughly heat vapors and hydro-carbon fuel, particularly the lower grades of such fuel, and combine the mixture with water vapor.

With these and other objects in view my invention consists in the construction, arrangement and combination of the various parts of the device, whereby the objects contemplated are attained, as hereinafter more fully set forth, pointed out in my claims and illustrated in the accompanying drawings, in which:

Fig. 1 shows a horizontal, sectional view through an attachment embodying my invention.

Fig. 2 shows a side elevation of the same, viewed from the side adjacent to the engine.

Fig. 3 shows a vertical, transverse sectional view taken on the line 3—3 of Fig. 1.

Fig. 4 shows a vertical, transverse, sectional view taken on the line 4—4 of Fig. 1; and

Fig. 5 shows a vertical, central, sectional view through the water plug device.

In the accompanying drawings, I have used the reference numeral 10 to indicate generally the outer casing of my improved device which comprises a tubular member having one closed end 11 as illustrated in Figs. 1 and 2.

Extending into the member 10 is what I shall call the heating tube 12 which terminates and is closed at 13 at a point spaced from the closed end 11. The casing 10 is connected at its end opposite the end 11 by a wall 14 which closes the end of the casing 10 opposite the end 11.

On opposite sides of the heating tube 12

the casing 10 is provided with horizontal partitions 15 which terminate short of the ends of said casing, as illustrated by dotted lines in Fig. 1.

Extending through the wall of the casing 10 at the side thereof are spaced tubes 16 designed to be connected with the exhaust manifold and extended inwardly to and communicating with the heating tube 12.

Extending through the side wall of the casing 10, and thence upwardly through the partition 15 on one side of the casing 10 and communicating with the compartment formed on one side of the partition 15 are spaced tubular members 17 designed to be connected with the intake manifold of an automobile engine.

Adjacent to the entrance to each tube 17 is a shoulder or the like 30 shown in Fig. 4, at the bottom of the casing 10 forming a trap for non-volatile oils, sediment or other material which cannot be properly vaporized. Such material may be drawn off through the cock 17.

Communicating with the rear compartment of the casing 10 is a tubular member 18 designed to be connected with an ordinary carbureter.

The heating tube 12 has an externally screw-threaded projecting end 19 designed to be connected with an exhaust pipe.

The interior of the casing 10 is provided with a plurality of spaced annular ribs 20 serving as baffles, and on the outside of the tube 12 is a similar series of baffle ribs 21 which are staggered with relation to the ribs 20.

For supplying moisture to the fuel mixture I have provided what I will call the water plug comprising a hollow tubular member 22 closed at its inner end, as shown in Fig. 5, and having a screw-threaded portion 23 extended from its inner end, and an externally screw-threaded portion 24 near its outer end, and a tubular externally screw-threaded extension 25 designed to be connected with a water conducting tube.

The wall of the water plug 22 between the screw-threaded portions 23 and 24 is provided with a series of openings 26.

A water conducting tube 22^a open at its lower end extends from the outer end of the plug 22 down into the plug past the openings 26 for conducting the water past said openings and preventing the engine suction from

drawing water drops or mist into the fuel mixture, before the water is thoroughly vaporized.

The water plug 22 is screwed into the upper part of the casing 10 and into the upper part of the tube 12, so that the lower closed end of the plug 22 is received within the tube 12 while the openings 26 communicate with both compartments of the casing 10.

In the practical use and operation of my improved attachment the device is mounted on the engine, and the tubes 16 are connected with the exhaust manifolds by means of bolts 15 extended through the flanges 16^a. The tubes 17 are connected with the intake manifold by means of bolts extended through the flanges 17^a, and the heating tube 12 is connected with the exhaust pipe.

20 The water plug is connected with a tube communicating with any suitable source of water supply.

It will be understood that any proper means such as a needle valve may be provided for regulating the flow of water to the water plug 22.

The tube 18 is connected with the carburetor or with the tube leading therefrom.

The suction of the engine will draw the fuel mixture from the carburetor through the tube 18 into the rear compartment of the casing 10.

It will be understood that after the engine has run a short time exhaust gases passing from the exhaust manifold through the tubes 16 and thence into and through the heating tube 12 will thoroughly heat the interior of my device.

40 The fuel mixture will whirl and strike against the baffle ribs 20 and 21 and will be mechanically broken up during its passage toward the ends of the casing 10 and around the ends of the partitions 15 and thence through the front compartment of 45 the casing 10 to the tubes 17 leading to the intake manifold.

A small amount of water received in the lower part of the water plug 22 will be subjected to the heat of the exhaust gases in 50 the heating tube 12 and will be vaporized and will pass into both compartments of the casing 10 and will there mingle with fuel mixture for furnishing moisture thereto.

The advantages of thoroughly breaking 55 up the hydrocarbon fuel mixture, heating it and adding moisture thereto are well-known and do not require further elaboration here.

By conducting the fuel mixture to the ends of the casing and returning it to the intake tubes, the mixture for all the cylinders is made uniform.

The device is so constructed that it is adaptable for use with any carburetor.

It will be noted that my device is of very 65 simple and durable construction and that

it may be quickly and easily mounted on or removed from an engine. By properly arranging the tubes and the flanges thereon, the device may be made to fit a variety of types of engines.

Some changes may be made in the construction and arrangement of the parts of my device without departing from the essential features and purposes of my invention, and it is my intention to cover by my 75 claims, any modified forms of structure or use of mechanical equivalents which may be reasonably included within their scope.

I claim as my invention:

1. A casing having closed ends, a heating 80 tube extended longitudinally into said casing, a tube extending through the wall of said casing to said heating tube, and designed to be connected with the exhaust manifold of an internal combustion engine, 85 partitions on opposite sides of said casing outside said heating tube terminating short of the ends of said casing, a tube extending through the wall of said casing and communicating with one of the compartments 90 therein designed to be connected with the intake manifold of an engine, and a tube communicating with the other compartment of said casing designed to be connected with a 95 source of fuel supply.

2. A casing having closed ends, a heating tube extended longitudinally into said casing, a tube extending through the wall of said casing to said heating tube, and designed to be connected with the exhaust 100 manifold of an internal combustion engine, 105 partitions on opposite sides of said casing outside said heating tube terminating short of the ends of said casing, a tube extending through the wall of said casing and communicating with one of the compartments therein, designed to be connected with the intake manifold of an engine, a tube communicating with the other compartment of said casing designed to be connected with a 110 source of fuel supply, and baffle devices in the compartments formed on the opposite sides of said partitions.

3. In a device of the class described, a casing closed at both ends, a heating tube 115 projected longitudinally into said casing, means for supplying heated gases to said heating tube, partitions in said casing on opposite sides of said tube terminating short of the ends of the casing, means for admitting fuel mixture into said casing on one side of the partitions, means for taking fuel mixture from the casing on the other side of the partitions, said last means comprising a tube, and a trap device formed in the lower 125 part of said casing.

4. In a device of the class described, a casing closed at both ends, a heating tube projected longitudinally into said casing, means for supplying heated gases to said 130

heating tube, partitions in said casing on opposite sides of said tube terminating short of the ends of the casing, means for admitting fuel mixture into said casing on one side of the partitions, means for taking fuel mixture from the casing on the other side of the partitions, said last means comprising

ing a tube, said casing having adjacent to the opening in said last described tube means for forming a trap, and a clean-out means 10 for said trap.

Des Moines, Iowa, May 4, 1918.

CLAUD E. MILLS.
